United States Patent Office

Des. 207,615
Patented May 9, 1967

207,615

BOILER

John C. Clever, River Hills, Walter J. Baron, Hubertus,
and Fred G. Wiegartz, Berlin, Wis., assignors to Cleaver-
Brooks Company, a corporation of Wisconsin

Filed June 30, 1966, Ser. No. 2,889

Term of patent 14 years

(Cl. D81—2)

FIG.1

FIG.2

FIG.3

FIG.4

FIG.5

FIG. 1 is a top plan view of a boiler, showing our new design;

FIG. 2 is a front elevational view of the boiler design illustrated in FIG. 1;

FIG. 3 is a rear elevational view of the boiler design illustrated in FIG. 1;

FIG. 4 is a front elevational view of the boiler design illustrated in FIG. 1; and

FIG. 5 is a rear elevational view of the boiler design illustrated in FIG. 1.

The dominant features of our design reside in the portions shown in full lines.

We claim:

The ornamental design for a boiler, as shown and described.
